UNITED STATES PATENT OFFICE

ANATOLE PROVOST, OF MONTREAL, QUEBEC, CANADA

GRATE BAR

Application filed May 16, 1929. Serial No. 363,606.

This invention relates broadly to furnace grates and more particularly to grates adapted for burning finely divided fuel such as sawdust, chips or the smaller grades of coal known as pea coal, screenings and the like, and the objects of the invention are to provide a grate composed of a series of bars so interlocked that each bar is held against accidental removal and against warping by the adjoining bars, and also to provide bars so formed as to define tortuous air passages therebetween through which the finely divided fuel will not pass readily.

A further object is to provide bars so formed and arranged that they positively hold one another against overturning.

A still further object is to provide for the easy removal of the bars when renewal is necessary.

Various other objects and the advantages may be ascertained from the following description and the accompanying drawings.

The invention resides, broadly speaking, in providing a series of bars each having a longitudinal groove in one side surface and a longitudinal rib in the opposite side surface adapted to enter the groove of the adjoining bar, so as to form tortuous passages between the bars through which finely divided fuel will not readily pass prior to being burned. The bars are adapted for assembly by a combined downward or lateral motion and are preferably arranged in sets with key bars between the sets serving to hold the bars of the sets against the lateral motion necessary for separation. The bars are supported by cross bearers having bar receiving notches preferably formed with one edge substantially vertical and the other edge inclined. One side surface of each bar below the groove or rib is substantially vertical, while the corresponding portion of the other side surface is materially inclined to correspond with the inclination of the notch edges, and the arrangement of bars in the grate is such that introduction of the key bar or bars forces the vertical surfaces of the adjoining bars against the vertical edges of retaining notches.

Referring to the drawings:—

Fig. 1 is a fragmentary cross sectional view of a grate formed according to the invention.

Fig. 2 is a perspective view of one of the bars.

Referring more particularly to the drawings, 11 designates one of any suitable number of cross bearers formed in its upper edge with two series of notches 12 and 12^a and a notch 13 located between the two first named series. The notches 12 and 12^a each have one substantially vertical edge 14 and one materially inclined edge 15. The vertical edges 14 of the notches of one series face the corresponding vertical edges of the notches of the other series as clearly shown. The notch 13 may be very slightly tapering, as shown, or may be otherwise formed.

Two series of bars 16, 16^a, are provided and are exactly similar except that they are formed or arranged left hand and right hand. Each bar presents a substantially vertical upper flank surface 18, one substantially vertical lower flank surface 19 and one materially inclined lower flank surface 20, the inclination of which corresponds with the inclination of the edges 15 of the notches in the cross bearers 11. Between the upper and lower vertical flank surfaces, each bar is provided with a longitudinal groove 21 and between the upper vertical and lower inclined flank surfaces, each bar is provided with a longitudinal rib 22 at the same level as its groove. The cross sectional profiles of the rib and groove of each bar are similar, so that the rib of one bar may enter the groove of the adjoining bar and, when the bars are suitably spaced, the surface of the rib and the surface of the groove will define a tortuous passage of substantially uniform width. Preferably, the lower surface of each rib is continuous with the lower inclined flank surface 20. Spacing lugs 23 are provided on the bars and are preferably located in the grooves 21, but may be located upon the ribs 22. These lugs are V-shaped, as shown in Figure 2, so that they will not only space the bars apart but will also centre the ribs in the grooves and operate to hold the bars against inde-

pendent vertical movement while the engagement is maintained. Starting at the opposite sides of the furnace, the bars are placed upon the cross bearers with a downward and outward movement corresponding substantially to the inclination of the notch edges 15 and, when thus inserted, the groove of each bar moves into embracing engagement with the rib of the previously inserted bar.

10 At the centre of the furnace, a key bar 24 is provided having a flat top and upper substantially vertical flanking walls, as in the case of the other bars. The intermediate portions of the flanking walls, designated 25, converge sharply at approximately the inclination of the upper edges of the adjoining ribs 22, and the lower flanking walls 26 are substantially vertical or converge slightly according to the shape of the retaining slot 13. The intermediate flanking walls 25 are provided with spacing lugs 27 to rest upon and enter between the ribs of the adjacent bars 16 to hold these bars against inward and upward movement necessary to disengage them from the bars outside them. The action of the key bar 24 is similar to the action of the key-stone of an arch and, when in place holds the lower vertical flanks 19 of the bars 16 against the vertical edges 14 of the notches, so that the bars are held against rocking or overturning.

Between the vertical upper flank surfaces 18, is provided one or more lugs 28, said lugs preferably forming part of one of said surfaces and are adapted to continuously keep said bars at a suitable distance from one another, thus eliminating the danger of clogging.

40 The key bar 24 is preferably provided at its lower end with an enlarged portion 29, which is centrally bored and threaded, and adapted to be engaged by the elongated bolt 30. The bolt is adapted to pass through a rod or tubular member 31 which engages the underside of the cross bearers 11, said bolt then engaging the threaded hole in the key bar. The object of this attachment is for firmly securing or locking the key bar to the cross bearers.

50 While the description thus far contemplates only one set of right hand and one set of left hand bars with a single key bar between them in the centre of the furnace, it will be understood that a complete grate may consist of as many series of bars and as many key bars as desired.

It will readily be seen from the drawings that each bar (excepting the key bar) is held against vertical movement relative to the adjoining bars by reason of engagement of its ribs in the groove of one adjoining bar (the relation of the faces 25 and 26 of the key bar being considered as forming a groove) and by reason of the rib of the other adjoining bar entering the groove. This interlocking

ing is effected at various points in the length of the bar according to the number of spacing lugs used and the bars may therefore be described as longitudinally interlocked. This longitudinal interlocking holds the bars securely against accidental displacement and also in large measure against warping. The ribs 22 form obstructions in the spaces between the upper vertical flanks of adjoining bars and in large measure prevent small particles of unburned fuel passing between the bars and being lost without obstructing the flow of air between the bars.

Having thus described my invention, what I claim is:—

1. A furnace grate unit having removable fuel supporting bars comprising a supporting member, a central bar detachably secured on the supporting member, a plurality of second bars mounted on the supporting member symmetrically disposed on each side of the central bar, means on the central bar for holding the adjacent bars against vertical movement, and means on the outer sides of each of the second bars for engaging the inner sides of the adjacent bars to prevent relative vertical movement therebetween.

2. A furnace grate unit having removable fuel supporting bars comprising a supporting member, a central bar detachably secured on the supporting member, a plurality of second bars mounted on the supporting member and symmetrically disposed on each side of the central bar, means on the central bar for holding the adjacent second bars against vertical movement and for holding the central bar and the adjacent second bars in spaced relation, and means on the outer sides of each of the second bars for engaging the inner sides of the adjacent second bars to prevent relative vertical movement therebetween and to hold the said bars in spaced relation.

3. A furnace grate unit having removable fuel supporting bars comprising a supporting member, a central bar detachably secured on the supporting member, a plurality of second bars mounted on the supporting member and symmetrically disposed on each side of the central bar, a depression on each side of the central bar, complimentary projections on the inner side of each adjacent second bar, bar spacing and interlocking lugs fitted into the depressions in the central bar and adapted to engage the complimentary projections on the adjacent second bars whereby the adjacent bars are held in spaced relation to the central bar and are held against vertical movement relative to the central bar, and tortuous air passages are formed between the central bar and each of the adjacent second bars, a depression in the outer side of each of the plurality of second bars, a complimentary projection on the inner side of each of the adjacent second bars, and bar spacing and interlocking lugs fitted into the depression in

the outer side of each second bar adapted to engage the complimentary projection on the inner side of each adjacent bar whereby each second bar is held in spaced relation to the 5 adjacent bars and each second bar is held against vertical movement relative to the adjacent second bars, and tortuous air passages are formed between the adjacent second bars.

4. A furnace grate unit having removable 10 fuel supporting bars comprising a supporting member which has a central depression and a plurality of second depressions symmetrically disposed on each side of the central depression, each of said second depressions having an outer vertical side and an inner inclined side, a central bar detachably secured in the central depression of the supporting member, a plurality of second bars symmetrically disposed on each side of the central bar, said second bars being shaped to fit into the secondary depressions in the supporting member, a depression on each side of the central bar, complimentary projections on the inner side of each adjacent second bar, bar 15 spacing and interlocking lugs fitted into the depressions in the central bar and adapted to engage the complimentary projections on the adjacent second bar whereby the adjacent second bars are held in spaced relation to the 20 central bar and are held against vertical movement relative to the central bar, and tortuous air passages are formed between the central bar and each of the adjacent second bars, a depression in the outer side of each of 25 the plurality of second bars, a complimentary projection on the inner side of each of the adjacent second bars, bar spacing and interlocking lugs fitted into the depression in the outer side of each second bar adapted to engage 30 the projection on the inner side of each adjacent bar whereby each second bar is held in spaced relation to the adjacent bars and each second bar is held against vertical movement relative to the adjacent second bars, and 35 tortuous air passages are formed between the adjacent second bars, spaced lugs located on the vertical sides of the central bar and near the top thereof, and spaced lugs located on the outer vertical side of each second bar and near 40 the top thereof, whereby lateral movement of each bar relative to the adjacent bars is deterred.

In testimony whereof I affix my signature.
ANATOLE PROVOST.
